FIG. 4 is a top plan view thereof;
FIG. 5 is a bottom plan view thereof;
FIG. 6 is a front elevation view thereof;
FIG. 7 is a rear elevation view thereof;
FIG. 8 is a side elevation view thereof; and
FIG. 9 is a cross-sectional view thereof along lines 9-9 in FIG. 4.
FIG. 10 is a top perspective view of an annular blade in accordance with a second embodiment;

FIG. 11 is a top perspective view of the annular blade independent from the exemplary rotary knife;
FIG. 12 is a bottom perspective view thereof;
FIG. 13 is a top plan view thereof;
FIG. 14 is a bottom plan view thereof;
FIG. 15 is a front elevation view thereof;
FIG. 16 is a rear elevation view thereof;
FIG. 17 is a side elevation view thereof; and
FIG. 18 is a cross-sectional view thereof along lines 18-18 in FIG. 13.
FIG. 19 is a top perspective view of an annular blade in accordance with a third embodiment;
FIG. 20 is a top perspective view of the annular blade independent from the exemplary rotary knife;
FIG. 21 is a bottom perspective view thereof;
FIG. 22 is a top plan view thereof;
FIG. 23 is a bottom plan view thereof;
FIG. 24 is a front elevation view thereof;
FIG. 25 is a rear elevation view thereof;
FIG. 26 is a side elevation view thereof; and
FIG. 27 is a cross-sectional view thereof along lines 27-27 in FIG. 22.
FIG. 28 is a top perspective view of an annular blade in accordance with a third embodiment;
FIG. 29 is a top perspective view of the annular blade independent from the exemplary rotary knife;
FIG. 30 is a bottom perspective view thereof;
FIG. 31 is a top plan view thereof;
FIG. 32 is a bottom plan view thereof;
FIG. 33 is a front elevation view thereof;
FIG. 34 is a rear elevation view thereof;
FIG. 35 is a side elevation view thereof; and,
FIG. 36 is a cross-sectional view thereof along lines 36-36 in FIG. 31.

The broken line showing of the rotary knife is provided for the purpose of providing environmental structure and forms no part of the claimed design. The dashed-dot-dot lines designate boundaries and form no part of the claimed design.
